ELECTRIC SWITCH

Eliot Noyes, New Canaan, Conn., assignor to General Electric Company, a corporation of New York

Filed Dec. 8, 1959, Ser. No. 58,598

Term of patent 14 years

(Cl. D26—13)

Fig. 1

Fig. 2

Fig. 3

FIGURE 1 is a front elevation view of an electric switch embodying my new design;

FIGURE 2 is a side elevation view of the switch of FIGURE 1;

FIGURE 3 is an end elevation view of the switch of FIGURE 1.

The dominant features of my design reside in the portions shown in full lines.

The side, end and back which are not shown, are conventional.

I claim:

The ornamental design for an electric switch, as shown and described.
